COMBINED WATCHCASE AND BRACELET

Edward P. Tyler, North Hollywood, Calif.

Application September 4, 1945, Serial No. 614,198

4 Claims. (Cl. 224—4)

1

This invention relates to watchcases, and has for an object the provision of a case for a wrist or a finger watch which includes the entire means for mounting the watch as an integral and permanent portion of the watchcase.

A more detailed object of my invention is to provide a watchcase, the opposite sides of which are extended to provide fingers so elongated and curved that they cooperate with each other to define a bracelet adapted to be slipped over a portion of a wearer's arm, to mount the watch in a convenient and readily visible position, thus avoiding the necessity of providing a band, strap, or the like in addition to the watchcase in accordance with more conventional practice.

A further object in this connection is to fashion the extended portion of the case so that they merge gradually into the body portion, thus presenting an article of jewelry of novel and unusually attractive design.

Another object of my invention is to provide a watchcase having an integral mounting as described, which is constructed of resilient material possessed of sufficient strength to permit its retaining a predetermined form whereby a bracelet or ring constructed in accordance with the principles of the present invention can be fitted precisely to a person's wrist or finger, and thus present an article of so-called "individualized" or custom made jewelry capable of commanding a higher sale value because of its having been made expressly for a certain wearer.

Still another object is to provide novel means for fastening the watch movement within its case whereby the fastening is of a permanent nature precluding removal of the movement without the destruction of at least a portion of its mounting unless special tools be employed, thus making any tampering with the movement by others than duly authorized, skilled craftsmen readily detectable.

The invention possesses other objects and valuable features, some of which, with those enumerated, will be set forth in the following description of the preferred embodiments of my invention illustrated in the drawing accompanying and forming part of the specification. It is to be understood that I do not limit myself to the showing made by the said drawing and description as I may adopt variations of the preferred forms within the scope of my invention as defined in the claims.

Referring to the drawings:

Figure 1 is a perspective view of a bracelet watchcase constructed in accordance with the principles of the present invention, showing the

2

inside surface of that portion in which the watch movement is mounted.

Figure 2 is a perspective view showing the exterior surface of that portion of the bracelet with which the watch movement is associated.

Figure 3 is an enlarged, longitudinal, medial sectional view taken through the bracelet of Figures 1 and 2, a portion of the figure being broken away to reduce its size.

10 Figure 4 is a view similar to Figure 1 showing a slightly modified form of bracelet watchcase.

Figure 5 is a view similar to Figure 2 showing the exterior surface of that portion of the bracelet of Figure 4 with which the watch movement is associated.

15 Figure 6 is a longitudinal, medial sectional view of the bracelet of Figures 4 and 5.

Referring first to that modification of my invention illustrated in Figures 1, 2, and 3, it will be observed that the bracelet 11 comprises a central body portion 12 extended at opposite sides to present fingers 13 integral with the body portion 12 and projecting oppositely therefrom so that by being curved through substantially 180 degrees, their extreme ends 14 approach each other, with the result that the combined body portion 12 and fingers 13 take the form of an elongated strip curved to substantially oval form. This strip is composed of suitable resilient material, any of the metals commonly employed in jewelry having been found satisfactory. It might be mentioned, however, that stainless steel has been found particularly appropriate as material of which to construct the bracelet 11, inasmuch as its severely plain and yet highly attractive finish has been found to blend perfectly with the plain, simple structural design of the bracelet 11. Moreover, stainless steel is characterized by the high coefficient of resiliency; and this is a rather essential characteristic of the material of which the bracelet 11 is formed, inasmuch as the bracelet is designed to remain in position upon the wearer's arm by being fitted nicely thereto either to his wrist or, in the event that the watchcase is de-

40 signed as a finger ring, upon the finger. In fact, the body portion 12 and fingers 13 are preferably of a relatively massive, heavy design, which permits forming the bracelet to the exact shape of the wrist or finger of the person by whom it is 45 to be worn so that it will retain the exact position which affords the greatest convenience to the user by locating its watch in that position wherein it is most readily visible. This feature also adds commercial value to the invention, because of the 50 higher sale value which can be commanded by a

custom made article which has been fashioned expressly for an individual.

The parts are so proportioned and arranged that the extreme ends 14 of the fingers 13 are separated from each other a distance slightly less than the minimum thickness of the wrist of the person for whom the bracelet 11 is fashioned. The bracelet is placed on the wearer's wrist by sliding the wrist laterally between the ends 14, with one end pressed rather firmly between the tendons just under the skin of the front of the wearer's wrist below the base of the thumb. As the wrist passes between the ends 14, a rotary motion of the bracelet 11 with respect to the wrist, causes the bracelet to assume a position upon the wrist with the ends 14 against the front of the wrist while the body portion 12 bears against the back of the wrist, thus placing the watch carried by the body portion 12 in the most convenient position for its ready visibility.

Of course, pressing one of the ends 14 so firmly into the flesh of the wrist will cause a certain amount of spreading of the fingers 13; and one of the details to be taken into consideration in the design of the bracelet 11 is to proportion the fingers to permit their being so spread. The fingers should be of sufficiently small cross-sectional area to permit their being flexed far enough so that the bracelet can be slipped into position in the manner described without discomfort to the wearer. Consequently, each of the fingers 13 is of considerably reduced cross-sectional area as compared to the body portion 12, thus assuring that the flexure of the bracelet coincident with placing the bracelet upon the wrist occurs solely in the fingers 13 and without any danger of deformation of the body portion 12 within which the watch 16 is carried.

In order to mount a watch movement 16 in the bracelet, a recess 17 is formed in the body portion 12, this recess being so proportioned that the movement 16 fits snugly therein, as by having its forward plate 18 fit relatively tightly into the bore of the recess 17 and bearing against the inner surface of a bezel 19 which defines the forward end of the recess 17. The bezel 19 also serves to retain the crystal 21 in its proper position before the face of the watch movement so as to exclude dust and moisture.

Thus it may be seen that the bracelet 11 actually constitutes the watchcase inasmuch as the watch movement 16 is fitted directly thereto.

A dustproof cover 22 is removably receivable within the back end of the recess 17, preferably being provided with the threads 23 engageable with complementary threads formed directly in the body portion 12 of the bracelet. The inner surface of the cover 22 is recessed as indicated at 24 to receive the back plate 26 of the movement 16, this plate 26 preferably being fitted accurately to the recess 24.

Actually therefore, the cover 22 constitutes the back of the watchcase which not only assists in excluding dust and moisture from the movement 16, but it also aids in the act of immobilizing the movement 16 within its case 12.

The winding stem 27 extends through a slot 28 which is formed in the back or undersurface of the body portion 12 in such position as to establish communication between the recess 17 and an aperture 29 which is formed in the body portion 12 at one side of the recess and at or near the base of one of the fingers 13. Hence, the knurled knob or head 31 by means of which the winding and setting stem 27 can be manipulated, is dis-

posed within the aperture 29. The parts are preferably so proportioned that the peripheral edge of the head 31 projects beyond both the front and the back surfaces of the body portion 12, thereby facilitating its being engaged between thumb and finger for either rotating as in winding the spring of the movement 16 or in setting the hands in the well known manner.

Figures 4, 5, and 6 disclose a modified form of my watchcase and bracelet, which differs from the first described modification in that the back 41 of the watchcase, instead of being separable from the remainder of the case 42, is integral therewith. This requires that the movement 43 be inserted into the recess 44 from the front and prior to the insertion of the crystal 46. In this modification, the crystal 46 serves as the member which locks the movement 43 so securely within the case 42 that it is effectually immobilized therein. This is accomplished by causing the crystal 46 to press firmly against the peripheral edge of the front plate 47 of the watch movement 43, thus causing the back plate 48 to press against the back 41 of the case with equal firmness. Preferably, the crystal 46 is anchored in position with respect to the case 42, behind a bezel flange 49 overlapping the peripheral edge of the crystal 46 and is permanently mounted within the case 42, i. e., so mounted therein that it cannot be removed without actual deformation or destruction of either the crystal 46 or the bezel 49, or both. Accordingly, a preferred manner of mounting the crystal 46 in the case 42 is that which forms the subject matter of my application Serial No. 384, 35767 filed March 22, 1941, now abandoned. The advantage of permanently mounting the crystal 46 in the case 42 is that it provides substantially positive assurance against tampering with the relatively delicate watch movement 43 by other than authorized persons possessed of the proper tools and skill. If others than authorized persons attempt to remove the crystal 46 and thus gain access to the watch movement 43, it will be unavoidable that at least some of the bezel 49 be destroyed if the crystal 46 is to be removed without its fracture, and therefore any such attempt will be readily detectable.

Since in the second described modification the watch movement 43 is inserted into the case 42 from the front of the recess 44, it is impractical to provide a slot extending from one end of the recess deep enough to receive the winding and setting stem 51 inasmuch as the forward end of such a slot would constitute a disfigurement of the outer visible face of the watchcase. Consequently, a preferred accommodation for the winding and setting stem 51 is an opening 52 extending from the recess 44 into an aperture 53 in the watchcase 42 adjacent the recess 44 and adjacent or in the base of one of the fingers 54. Consequently, it is necessary to remove the knurled head 56 from the stem 52 before the movement is inserted into the recess 44 and then to insert the movement 43 but first slipping the end of the stem 51 through the opening 52 and then slipping the movement 43 into the recess 44 in a twisting movement. Thereafter, the head 56 can be secured to the exposed end of the stem 51 in the usual manner.

I claim:

1. As a novel article of jewelry, a watch bracelet comprising an elongated strip of resilient material having its end portions curved to substantially oval form, but spaced apart sufficiently to permit passage of a wearer's wrist therebe-

tween without spreading the ends of said strip to the extent of exceeding the elastic limit of said material, said strip having a recess therein, a watch movement fitted directly into said recess, and a crystal fitted to said strip with its edge encircling said recess and retaining said movement within said bracelet.

2. As a novel article of jewelry, a watch bracelet comprising an elongated strip of resilient material having its end portions curved to substantially oval form, but spaced apart sufficiently to permit passage of a wearer's wrist therebetween without spreading the ends of said strip to the extent of exceeding the elastic limit of said material, said strip having a recess therein, a watch movement fitted directly into said recess, means integral with said strip defining a bezel encircling said recess, and a crystal seated under said bezel said movement being rigidly retained in said recess by said crystal and bezel.

3. As a novel article of jewelry, a watch bracelet comprising an elongated strip of resilient material having its end portions curved to substantially oval form, but spaced apart sufficiently to permit passage of a wearer's wrist therebetween without spreading the ends of said strip to the extent of exceeding the elastic limit of said material, said strip having a recess therein, a watch movement fitted directly into said recess, and a crystal fitted to said strip with its edge encircling

said recess and retaining said movement within said bracelet, said movement being removable from said bracelet only by destruction of said crystal.

4. As a new article of manufacture, a watch-case comprising a central body portion apertured in its outer face to receive a watch movement, and extended laterally outwards at opposite sides thereof to define laterally extending fingers integral with said body portion, said fingers being curved and their ends extending toward each other, whereby said body portion and curved fingers cooperate in defining a bracelet, one of said fingers having an opening therethrough adjacent said recess for the reception of the winding crown of said movement, and said one of said fingers and said body portion having a hole therein interconnecting said aperture and said opening, and adapted to receive the winding stem of said movement.
